UNITED STATES PATENT OFFICE.

FREDERICK WESTERBECK, OF ST. LOUIS, MISSOURI.

REFRIGERATOR.

979,814.

Specification of Letters Patent. Patented Dec. 27, 1910.

Application filed May 19, 1910. Serial No. 562,212.

To all whom it may concern:

Be it known that I, FREDERICK WESTERBECK, a citizen of the United States of America, residing in the city of St. Louis and 5 State of Missouri, have invented certain new and useful Improvements in Refrigerators, of which the following is a full, clear, and exact description, reference being had to the accompanying drawings, forming part of 10 this specification.

My invention relates to a refrigerator for holding bottles in order that their contents may be cooled and maintained in a cooled condition pending the consumption of such 15 contents; and it has for its object the production of a refrigerator of this description so constructed as to provide for the bottles being automatically delivered to a point at which they may be extracted singly from 20 the refrigerator without the necessity of opening the door of the refrigerator with an objectionable loss of low temperature in the refrigerator incident to the escape of cooled air and the inrush of warmer air.

25 Figure I is a view partly in end elevation, and partly in vertical cross section of my refrigerator; the refrigerator door being partly broken away to afford a view of the interior of the refrigerator. Fig. II is in part a 30 side elevation, and in part a vertical longitudinal section, a portion of the side wall being broken out. Fig. III is a horizontal section taken on irregular line III—III, Fig. II.

35 In the accompanying drawings: 1 designates the side walls, 2 the bottom, and 3 the top of the casing of my refrigerator. The refrigerator, as shown in the drawings, has a doorway at each of its ends that is normally closed by a door 4, and is subdivided 40 interiorly into two storage compartments A, the subdivision being produced by the presence of a double partition extending transversely of the refrigerator and comprising 45 partition walls 7 and 8, spaced apart from each other.

9 designates an ice pan suitably supported above the storage chambers A and in which is a drain outlet 10 surmounted by a plate 50 form 11 on which ice may be placed.

12 is a drip pan beneath the ice pan and into which the water from the melting ice falls as it passes through the drain outlet of the ice pan to be conducted from the drip 55 pan through a drain pipe 13, that leads to the exterior of the refrigerator.

In each door 4 is a withdrawal aperture 5 located at the bottom and near one of the side edges of the door, this opening being provided to permit the withdrawal of bottles from the refrigerator without the necessity of opening the door in which the aperture is located. Each withdrawal aperture 5 is normally closed by a stopper 6 that may be readily and quickly withdrawn from 65 and replaced in the aperture.

14 designates runway rails extending transversely of the refrigerator in the storage compartments, and located at the rear of such compartments. These runway rails 70 are shorter than the width of the storage compartment in which they are present so that they extend from one side of the compartment to a point distant from the other side of the compartment, and they are inclined downwardly from their ends that terminate at sides of the storage compartments. The runway rails are spaced apart from the partition wall at the back of the storage compartment in which the rails are located, and 75 their highest ends are connected to side walls of the refrigerator casing, while their lower ends extend rearwardly to, and are attached to, the adjacent partition wall. Furthermore, the runway rails 14 are arranged alternately so that while one rail extends from one side of the storage compartment to a point remote from the other side, the next rail, which extends downwardly and in an opposite direction from the second side of 80 the storage compartment, terminates at a distance from the first mentioned side of such compartment, thereby providing for a bottle resting on an upper rail traveling downwardly thereon until it reaches the 85 lower end of the rail, then descending through the space between the lower end of this rail and the opposing side of the refrigerator onto the next lowermost rail to descend thereon in a direction of travel the 90 reverse of its travel on the upper rail until it descends therefrom at the side of the storage chamber at which it started, to again reverse its travel on the next succeeding rail.

15 designates forward runway rails in a storage compartment that are so mounted therein as to extend transversely of the storage compartment, and in inclined directions corresponding substantially to the inclines 100 of the runway rails 14. These forward runway rails are, however, intended to support 105 110

the necks of bottles, and they are, therefore, elevated slightly above the planes occupied by the mating runway rails 14 to provide for the bottles being upheld in horizontal positions while they are descending upon the runway rails. The forward runway rails extend across the compartments in substantially the same manner as the rear rails; and to permit of the descent of the necks of the bottles from the lower end of each rail onto the next lowermost rail, the forward rails extend forwardly at 16 to furnish gaps between such lower ends and the opposing sides of the refrigerator casing, which gaps are of less width than those between the lower ends of the rear rails and the opposing sides of the casing, and inasmuch as the lower ends of the forward rails may not be connected to the adjacent door 4 and permit 20 of its being opened, said rails are provided with extensions 17 that lead to, and are attached to, the adjacent casing wall.

It will be readily appreciated that in the practical use of my refrigerator, a storage compartment may be filled with bottles, as shown in the drawings, the bottles being arranged upon the rear and forward runways. Further, that the lowermost bottles in the compartment will rest upon runway rails 30 at the bottom of the compartment, and one of the bottles will be present on these lower runway rails, at the location of the withdrawal aperture 5 in the door closing the compartment, ready to be withdrawn from 35 the refrigerator upon the removal of the stopper 6. It should be stated that the lowermost runways, which have, for clearness, been designated 14' and 15', extend continuously across the storage chamber, as 40 seen in Fig. I and in the compartment at the right-hand end of Fig. III. Upon the withdrawal of a bottle through the withdrawal aperture 5, there is downward movement of the remaining bottles upon the runway rails, so that the bottle next succeeding that which was withdrawn moves into place 45 opposite the withdrawal aperture. This action of the bottles continues as long as there are bottles in the storage compartment.

50 I have shown my refrigerator as containing two storage compartments A, but it is obvious that the refrigerator may be made with a single compartment inasmuch as the two compartments are provided merely for 55 the purpose of increasing the capacity of the refrigerator. It is furthermore obvious that while I have shown the refrigerator so constructed as to permit of the withdrawal of the bottles through the withdrawal aperture 60 5 in the door of the refrigerator, the

runway rails might be so disposed in the storage chamber as to cause the bottles to be presented toward a withdrawal aperture in the side of the refrigerator, and through which the bottles could be withdrawn as 65 readily as in the instance of arranging the parts in the manner shown in the drawings.

I claim:

1. In a bottle storage refrigerator, a housing containing a storage chamber, a plurality of rear runways in said storage chamber arranged one above another, each alternate runway being inclined downwardly in a direction the reverse of the surmounting runway, the lower ends of the runways 75 being separated from the housing walls opposing such lower ends to provide spaces through which bottles may descend to the next lowermost runways and forward runways elevated above the rear runways. 80

2. In a bottle storage refrigerator, a housing containing a storage chamber, a plurality of rear runways in said storage chamber arranged one above another, each alternate runway being inclined downwardly 85 in a direction the reverse of the surmounting runway, the lower ends of the runways being separated from the housing walls opposing such lower ends to provide spaces through which bottles may descend to the next lowermost runways; said housing being provided with an aperture through 90 which the bottles may be withdrawn when they have descended on said runways and forward runways elevated above the rear 95 runways.

3. In a bottle storage refrigerator, a casing containing a storage chamber and having a doorway therein, a door closing said doorway, a plurality of rear runways in said storage chamber arranged one above another, each alternate runway being inclined downwardly in a direction the reverse of the surmounting runway, the lower ends of the runways being separated from the casing walls opposing such lower ends to provide spaces through which bottles may descend to the next lowermost runways, the said door being provided with an aperture 100 at the lower end of the lowermost of said 105 runways, and a stopper by which said aperture is normally closed and forward runways elevated above the rear runways. 110

In testimony whereof, I have hereunto affixed my signature, this 16th day of May, 115 1910.

FREDERICK WESTERBECK.

In the presence of—

E. B. LINN,

A. J. McCauley.
